UNITED STATES PATENT OFFICE.

FRANK SAGE, OF HASTINGS, MICHIGAN, ASSIGNOR TO HASTINGS WOOL BOOT COMPANY, A CORPORATION OF MICHIGAN.

METHOD OF MANUFACTURING FELT ARTICLES.

1,201,352.

Specification of Letters Patent. Patented Oct. 17, 1916.

Application filed February 15, 1915. Serial No. 8,331.

To all whom it may concern:

Be it known that I, FRANK SAGE, a citizen of the United States, residing at Hastings, in the county of Barry and State of Michigan, 5 have invented certain new and useful Improvements in the Method of Manufacturing Felt Articles, of which the following is a full, clear, and exact description.

This invention relates to the method of 10 manufacturing felt articles, and has for an object to produce such articles with a portion thereof having two separate layers, said layers being integrally united into a single ply in the remaining portion of the article.

15 My method is applicable to the manufacture of felt boots, and it is for this that I intend to make the principal use of it, though I do not wish to limit myself to such use.

20 While the ordinary felt boots, such as are commonly used in combination with rubber shoes, subject the wearer to great discomfort by reason of the ingress of snow and water about the tops of the shoes, heretofore no 25 one has succeeded in devising means for effectually overcoming this difficulty. By my method, I produce a felted or felt boot with an apron integral with the leg portion and dependent therefrom to overlap the top 30 of the shoe, capable of being buckled tightly about the same, thereby covering the opening between the boot proper and the top of the shoe.

35 This construction effectually prevents any ingress into the shoe of snow or water, inasmuch as any which may strike the leg of the boot is deflected by the apron over the outside of the rubber shoe and thereby prevented from running down inside as in the 40 case with the conventional article.

I accomplish my result by a new and original method, more fully set forth in the following specification and claims, and illustrated in the accompanying drawing forming 45 a part thereof, wherein—

Figure 1 is a perspective view of a felt boot constructed according to my method, showing also a rubber shoe in position thereon, and Fig. 2 is a vertical sectional view 50 of the same.

In the construction of an article according to my method, I first make a felted cone on a form by the usual process of felting the wool or flock. About the cone thus formed 55 I apply a piece of non-felting material,

This piece is placed so that it covers a belt or zone about the portion where it is desired to form the apron or collar, and those parts where but one layer is desired are left exposed. I next apply a second layer of unfelted material, covering both the non-felting piece and the uncovered portion of the 60 felted cone. The whole is again subjected to the felting process, the last stratum of wool being integrally felted into the portion of the cone not covered by the non-felting cover, and forming a separated layer at the places where the two plies are divided by said cover. The structure as thus built up is removed from the form, and finished 65 according to the usual practice by shrinking and drying on a form of the desired shape.

In the drawing I show a finished boot made by my method and the mode of co-operation of the parts with a rubber shoe 70 or galosh. The original first ply of felt constitutes the foot portion 3 of the finished boot, the apron or collar 4 consists of the second ply of felted wool where it was separated from the ply 3 by the non-felting stratum, and the leg portion 5 is formed of both the first and second layers 3 and 4 75 felted into an integral structure at that part of the original cone where no intermediate layer of non-felting material was placed. In the finished boot the exposed upper edge 80 is bound with fabric 6, the draw loops 7 are attached, the apron 4 is cut as at 8, and the buckles 9 are riveted in place to 85 permit a tight fit over a rubber shoe 10.

A boot constructed as above described 90 keeps the feet of the wearer dry and warm by preventing snow and water coursing down the leg into the interior of the galosh. Inasmuch as the apron is joined integrally 95 with the boot-leg, there is no unsightly thickened lap-joint to cause discomfort to the wearer, and the whole structure is not noticeably more cumbersome than the ordinary boot.

Having described my invention, what I claim and desire to protect by Letters Patent is:

1. The method of manufacturing felt articles which consists in felting a ply of material on a suitable form, partially covering said ply with a layer of non-felting material, superposing on said ply and non-felting material a layer of unfelted material, 105 felting said layer so that the same is felted 110

integrally with that part of said ply not covered by the non-felting material, and shaping and setting the whole in the desired shape.

- 5 2. The method of manufacturing felt articles which consists in felting a ply of material on a suitable form, partially covering said ply with a layer of non-felting material, superposing on said ply and non-felting material a layer of unfelted material, felting said layer so that the same is felted integrally with that part of said ply not covered by the non-felting material, shrinking the whole, and finally drying in the desired shape.
- 10 3. The method of manufacturing felt articles with an apron which consists in applying to a form a layer of felted material, and a layer of unfelted material partially separated by a layer of non-felting material, felting said unfelted layer integrally with
- 15
- 20

said felted layer, said non-felting layer preventing union of those portions of said layers adjacent thereto, removing the felted material from the form, shrinking the same, 25 and finally drying in the desired shape.

4. A boot having its walls composed throughout of felted wool flock, comprising an integral foot-and-leg portion consisting of a single ply and an apron portion 30 integrally joined to the foot-and-leg portion consisting of a single ply, both the inner and outer surfaces of the two plies at the junction thereof being flush with one another.

Signed at Hastings, this 8 day of February, 1915.

FRANK SAGE.
